STRAP TENSIONING TOOL

Michael O. Derrickson, Norwood, Pa., assignor, by mesne assignments, to FMC Corporation, San Jose, Calif., a corporation of Delaware

Filed Jan. 14, 1963, Ser. No. 73,177

Term of patent 14 years

(Cl. D54—13)

FIG. 1 is a top plan view of a strap tensioning tool showing my new design;

FIG. 2 is an elevational view showing one side of the tool;

FIG. 3 is a front elevational view of the tool;

FIG. 4 is an elevational view showing the other side of the tool; and

FIG. 5 is a rear elevational view of the tool.

The lines on the side of the nut head in FIGS. 1, 2, 4, and 5, which represent knurling, are understood to con-

tinue throughout the plain area on the side of said element.

I claim:

The ornamental design for a strap tensioning tool, as shown and described.
